WIRE LINE TWISTER

James A. Smethers, Andrews, Tex.

Application March 26, 1935, Serial No. 13,083

7 Claims. (Cl. 81—87)

This invention relates to adjustable wrenches. It is a principal object of this invention to provide a wrench wherein a limited closing movement of the jaws may be quickly and easily accomplished, and at the same time great pressure may be exerted between the jaws.

Another object of this invention is to provide a wrench having adjustable means whereby the limited closing movement may be made to occur at any desired opening of the jaws.

Still another object of this invention is to provide a wrench wherein the adjusting means is at all times locked against accidental change.

More particularly this invention relates to a wrench especially adapted to grip a steel cable or "wire line" in oil field work and has as its specific objects: First, to provide a wrench which may be easily and quickly caused to grasp such a cable, and with great pressure, and which may be readily released; second, to provide such a wrench which may be adjusted to accommodate varying sizes of cables.

In such wire line wrenches, when the tension or twist of the line accumulates, it is not uncommon for the wrench to slip, or get away from the workman, and the wrench may be thrown several feet. By the aid of the present invention, the grip of the wrench is effected in a positive manner so that the wrench cannot be freed until the jaw locking device is purposely released.

This invention possesses many other advantages, and has other objects which may be made more easily apparent from a consideration of one embodiment of the invention. For this purpose there is shown a form in the drawing accompanying and forming part of the present specification. I shall now proceed to describe this form in detail, which illustrates the general principles of my invention; but it is to be understood that this detailed description is not to be taken in a limiting sense, since the scope of my invention is best defined by the appended claims.

Referring to the drawing:

Figure 1 is an elevation of a wrench gripping a wire line;

Fig. 2 is a fragmentary elevation, partly in section, the jaws being shown in open positions; and

Figs. 3 and 4 are detail sections on an enlarged scale as seen on correspondingly numbered planes of Fig. 1.

Referring with more particularity to the drawing, a steel cable or "wire line" is indicated by 5 in Fig. 1, and is shown as gripped between a movable jaw 6 and a stationary jaw 7. Each

jaw is provided with a hardened steel insert 8, provided with suitable teeth, disposed in an arcuate manner which actually engage cable 5. These inserts are held in place in the jaws by being dovetailed at their inner corners as indicated by 9, set screws 10 serving to hold them against slipping.

The stationary or lower jaw 7 is formed integrally with a frame 11, suitably designed for lightness and strength and arranged to receive 10 an extension handle 12. On the back of the upper part of the handle member, a guide 13 is formed to receive the supporting arm 14 of the movable or upper jaw 6. A boss 15 is formed at the lower part of the guide and has a pin 16 15 passing through it, the outer ends of which serve to pivotally support the operating member 17.

This operating member, as clearly shown in Figs. 2 and 4, consists of a bar or handle 18, with a pair of side flanges 19 and 20 forming cams.

The movable arm 14, as shown in Fig. 3, has flat sides which cooperate with the guide 13 to maintain jaws 6 and 7 in alignment. However, arm 14 has an extension 21, which is threaded, 25 extending through boss 15, and carrying the cam follower on nut 22. This nut 22 has an upper portion 23, with flat sides and a lower projecting portion or flange 24. The upper surface of the flange 24 is engaged by the faces of cams 19 and 20 while opposite sides of the upper portion 23 are engaged by the inner surfaces of the flanges or cams 19 and 20.

A light compression spring 25 is confined between the bottom of arm 14 and boss 15 encircling threaded extension 21 and urging jaws 6 and 7 apart, the amount of this opening being limited by the engagement of cam follower 22 and cams 19 and 20.

From an inspection of the drawing it will be plain that as cams 19 and 20 are rotated in a counterclockwise direction from the position shown in Fig. 2 to that shown in Fig. 1, the action of the cam on the cam follower 22 will urge jaws 6 and 7 together; and further that the position of cam follower 22 on stem 21 will determine the space between the jaws when the cam has completed its movement. Thus when it is desired to alter the size cable that the wrench will grip, the operating member is turned to the 50 position of Fig. 2, jaw 6 is pressed downwardly against spring 25 until the sides of the nut 23 of the cam follower 22 are free of the inner surfaces of flanges 18 and 19. The flange portion 24 will then be opposite clearance space 26 in the 55

handle and the follower can readily be turned on the threaded stem 28 to vary the effective length thereof. This will alter the spacing of jaws 6 and 7 at the closed position thereof.

5 Due to the arcuate configuration of the teeth in inserts 8, it is apparent that the wire 6 is positively gripped, and cannot be released until the positive lock provided by cam 18 is released.

I claim:

- 10 1. In a wrench, a pair of clamping jaws, a movable supporting arm structure for one of said jaws, and a cam operating to move said arm structure toward clamping position, said structure having adjustment means cooperating with said cam for varying the jaw opening in clamping position, said adjustment means and cam having cooperating locking surfaces for maintaining said means in adjusted position, said supporting arm structure also being movable independently of said cam toward clamping position to free said locking surfaces.
- 15 2. In a wrench, a frame having a stationary jaw supported thereon, a movable arm with a jaw supported thereon adapted to cooperate with said stationary jaw, a guide for said arm on said frame, a compression spring urging said jaws to open position, an operating member including a cam pivoted on said frame arranged to urge said jaws to closed position, a cam follower secured to said movable arm arranged to cooperate with said cam to urge said jaws to closed position, the position of said cam follower in relation to the jaw on said movable arm being variable, whereby the opening between said jaws may be varied, and locking means operable by said cam to maintain said cam follower in adjusted position, said supporting arm structure also being movable independently of said cam toward clamping position to free said locking surfaces.
- 20 3. In a wrench, a frame having a stationary jaw supported thereon, a movable arm with a jaw supported thereon adapted to cooperate with said stationary jaw, a threaded extension on said arm, a guide for said arm on said frame, a compression spring urging said jaws to open position, an operating member including a cam pivoted on said frame, a cam follower threadedly mounted on said extension and arranged to cooperate with said cam to urge said jaws toward closed position, the position of said cam follower in relation to the jaw on said movable arm being variable whereby the opening between said jaws may be altered, said cam follower having a face arranged to engage a face of the cam in response to a force normally exerted by said compression spring and restrain said follower against rotation unless said faces are disengaged by pressure exerted against said compression spring.
- 25 4. In a wrench, a frame, a stationary jaw supported on said frame, a movable arm, a jaw supported on said arm and adapted to cooperate

with said stationary jaw, said arm having an extension, said frame having a guide for the arm, an operating member pivoted to the frame including a cam, and means cooperating with the cam and longitudinally adjustable on said extension for varying the jaw opening, said means and cam having cooperating locking surfaces for maintaining said means in adjusted position.

5 5. In a wrench, a frame, a stationary jaw supported on said frame, a movable arm, a jaw supported on said arm and adapted to cooperate with said stationary jaw, said frame having a guide for the arm, said arm having an extension, said guide including a boss through which said extension passes, a compression spring disposed around the extension and urging the arm toward jaw opening position, an operating member including a cam pivoted to the boss, a cam follower mounted on said extension and cooperating with said cam to move the arm toward jaw closing position, said cam follower being adjustable on said extension for varying the jaw opening in closing position, and locking means to maintain said follower in adjusted position.

6 6. In a wrench, a frame, a stationary jaw supported on said frame, a movable arm, a jaw supported on said arm and adapted to cooperate with said stationary jaw, said frame having a guide for the arm, said arm having an extension, said guide including a boss through which said extension passes, a compression spring disposed around the extension and urging the arm toward jaw opening position, an operating member including a cam pivoted to the boss, a cam follower mounted on said extension and cooperating with said cam to move the arm toward jaw closing position, said cam follower being adjustable on said extension for varying the jaw opening in closing position, and locking means on said follower and cam operable by said spring to maintain said follower in adjusted position.

7 7. In a wrench, a frame, a stationary jaw supported on said frame, a movable arm, a jaw supported on said arm and adapted to cooperate with said stationary jaw, said frame having a guide for the arm, said arm having an extension, said guide including a boss through which said extension passes, a compression spring disposed around the extension and urging the arm toward jaw opening position, a nut threaded upon the extension and beyond the boss, said nut having flat sides, as well as a flange, and an operating member pivoted to the boss and having side flanges forming a cam cooperating with the flange on the nut to move the arm toward jaw closing position, said side flanges engaging the flat sides of the nut to restrain the nut against rotation unless the nut be freed from said side flanges by a pressure exerted against said compression spring.

JAMES A. SMETHERS.
